CARBONATED BEVERAGE CONTAINER

John J. Heydon, 611 W. Hill St., Fullerton, Calif., and Dean W. Myers, 2815 Lafayette Ave., Newport Beach, Calif.

Filed Sept. 30, 1963, Ser. No. 76,789

Term of patent 14 years

(Cl. D2—3)

FIG. 1

FIG. 2

FIG. 3

FIG. 4

FIG. 1 is a perspective view of a carbonated beverage container showing our new design;

FIG. 2 is a front view thereof;

FIG. 3 is a bottom view thereof; and

FIG. 4 is a side view thereof.

The side opposite that shown in FIG. 4 is a mirror image thereof.

We claim:

The ornamental design for a carbonated beverage container, as shown and described.
